UNITED STATES PATENT OFFICE.

LESTER A. WERNERY, OF BROOKLYN, NEW YORK, ASSIGNOR TO BURNHAM C. STICKNEY, OF ELIZABETH, NEW JERSEY.

INDEX.

to form a unit having a solid base, said partitions being of gradually increasing heights and stiffly supported by said butts.

3. A multiple index-card receptacle comprising a stepped series of butts upon which to rest the cards to bring their top edges into echelon arrangement, partitions for confining cards that rest upon said butts, said partitions and butts formed of paper or cardboard and glued or fastened together facewise to form a unit having a solid base of stepped formation, and a back to which said butts are secured, said back having an index projecting therefrom.

15. 4. An index-card system comprising a series of units, each having a stepped series of butts upon which to rest the cards to bring their top edges into echelon arrangement, partitions for confining cards that rest upon said butts, said partitions bearing individual legends to call attention to the absence of cards; and index-cards inserted between said partitions; each legend hidden by the card but in position to be rendered visible when the card is removed.

25. 5. An index-card system comprising units, each having a stepped series of butts upon which to rest the cards to bring their top edges into echelon arrangement, partitions for confining cards that rest upon said butts, said partitions having their upper corners cut away for clearance in removing and replacing the cards, and cards inserted between said partitions, each card covering up the partition in rear thereof.

30. 6. A card-index comprising a series of units, each comprising a stepped set of butts with intervening partitions, and a back, said butts, partitions and back being secured together, and said backs having a series of visible projections bearing a series of indexing characters, and index-cards of uniform sizes inserted between said partitions and resting upon said butts, all of the top borders of the cards being constantly visible in all of the units.

40. 7. An index-card system comprising a general receptacle or unit divided by a series of partitions into individual card-receptacles or pockets, and index-cards inserted between said partitions, each partition being made of paper or thin card, said receptacle comprising a base consisting of pasteboard butts of assorted sizes, and having a stepped arrangement and interleaved with said partitions of similarly assorted sizes and adherent thereto, to make

a solid base or block, the partitions being stiffly supported by said butts, the upper edges of the butts forming steps, upon which rest the index-cards, all with their upper borders exposed to view.

5. 8. A card-index system comprising a tray, box or receptacle, a series of units fitted one behind another in said receptacle, each unit comprising a series of steps and a stepped series of partitions, and index-cards inserted between the partitions and resting upon the steps, said index-cards both insertable and removable independently of one another and of uniform size and standing one above another with their top borders exposed to render visible the index matter placed upon said top borders, the rear portion or partition of said unit having its top edge about level with the rearmost of said index-cards.

15. 9. A card-index system comprising a tray, box or receptacle, a series of units fitted one behind another in said receptacle, each unit comprising a series of steps and a stepped series of partitions, and index-cards inserted between the partitions and resting upon the steps, said index-cards of uniform size and standing one above another with their top borders exposed to render visible the index matter placed upon said top borders, all the indexes upon all of the cards in all of the units in said tray being constantly visible; said partitions bearing exposable individual legends to call attention to the absence of cards, each legend being hidden by the adjoining index-card.

20. 10. A card-index system comprising a tray, box or receptacle, a series of units fitted one behind another in said receptacle, each unit comprising a series of steps and a stepped series of partitions, and index-cards inserted between the partitions and resting upon the steps, said index-cards of uniform size and standing one above another with their top borders exposed to render visible the index matter placed upon said top borders, all the indexes upon all of the cards in all of the units in said tray being constantly visible; said partitions having their upper corners cut away on the sides for clearance in removing and replacing the cards.
